UNITED STATES PATENT OFFICE.

JOHN H. COBEL, OF ST. JOSEPH, MISSOURI.

FOLDABLE UMBRELLA.

1,217,709.

Specification of Letters Patent. Patented Feb. 27, 1917.

Application filed November 19, 1915. Serial No. 62,362.

To all whom it may concern:

Be it known that I, JOHN H. COBEL, a citizen of the United States, residing at St. Joseph, in the county of Buchanan and State 5 of Missouri, have invented new and useful Improvements in Foldable Umbrellas, of which the following is a specification.

The present invention has relation to umbrellas of that class which will not only open 10 and close in the ordinary manner but which also may be collapsed or folded and reduced in size to an extent for convenience in transportation and storage and further permits the umbrella being carried in a 15 satchel or trunk.

The primary object of the invention is the provision of a device of the above stated character whereby the sections constituting the stick portions of the umbrella are so 20 formed as to prevent any accidental rotary movement of the sections, with respect to one another when the sections of the stick are in a folded position.

With the above and other objects in view, 25 the invention consists in the novel features, details of construction and combination of parts which will hereinafter be more fully set forth, illustrated in the accompanying drawing and pointed out in the appended 30 claim.

In the drawing:

Figure 1 is a vertical section of an umbrella in an unfolded position;

Fig. 2 is an enlarged sectional view of an 35 umbrella showing the top open as in Fig. 1 with certain portions broken away for convenience of illustration;

Fig. 3 is a cross section on line 7—7 of Fig. 1;

Fig. 4 is a detail section of the runner in 40 active position;

Fig. 5 is a detail longitudinal section of the rib sections; and

Fig. 6 is a detail cross section of the rib 45 sections.

Referring more particularly to the drawing, 5 comprises an umbrella stick composed of an upper split tubular section 6, an intermediate split tubular section 7 and a lower 50 tubular split section 8, the tubular section 8 being provided with a handle portion 9. In cross section the said upper and intermediate sections of the stick are preferably hollow and telescopically arranged one within the 55 other and the split longitudinal edges of the sections partially overlap one another as

at 9' to provide a substantially V-shaped longitudinally disposed groove 10 which will permit of a sliding movement of the intermediate section 7 within the upper section 6 and prevent the intermediate section from any accidental rotary movement with respect to the upper section when the said sections are in either a folded or extended position. The top section 6 is stamped out at 60 points throughout its length to provide an intermediate slot 11 and a lower slot 12, while the intermediate or middle section of the stick has secured to its inner circumference by means of a fastener 13, a resilient 65 keeper 14 adapted to engage in the slot 12 of the top section of the stick when the sections are in an unfolded position, and retaining the middle section 7 and top section 6 against accidental movement. The lower 70 end of the middle section 7 is internally threaded as at 15 for threadedly receiving the threaded extension 16 of the lowermost section 8 of the stick, and for operatively connecting the latter mentioned section with 75 the middle section.

Slidably mounted on the sections constituting the stick 5 is the usual runner 17, which like the stick sections is circular in cross section and split throughout its longitudinal extent, the free longitudinal edges formed by the splitting of the runner being partially arranged in overlapping position to provide a longitudinally disposed V-shaped groove 18 of substantially V-shaped 80 configuration in cross section. The protruding longitudinal edge of the middle and upper stick sections form ribs 19, the rib 19 of the middle section engaging in the V-shaped groove of the upper stick section, 85 while the rib 19 of the upper stick section engaging in the V-shaped groove of the runner 17, whereby to accurately guide the runner upon the sliding movement of the stick sections and also preventing any accidental 90 rotary movement thereof, during the adjustment of the runner on such sections. This runner 17 has formed on its upper end a collar 21 formed with a series of spaced 95 concentrically arranged slots 22, certain of said slots having pivotally connected therein the usual stretchers 23, such stretchers having pivotal connection at their opposite ends with the lowermost rib sections 24, which together with the upper section 25 comprises 100 the umbrella frame. The uppermost rib section 25 embodies the usual steel ribs now 110

employed in umbrellas and has formed on its free end a knob 25' which is slidably mounted in the substantially C-shaped lowermost rib sections 24 to make an easy 5 operation of the same and prevent displacement of the rib sections from one another when the umbrella is hoisted.

The uppermost rib sections 25 are pivotally connected in the notches 26 of the enlarged circular head 27 of the plug 28. This 10 plug 28 is of cylindrical form and provided with external threads 29 for threadedly connecting in the upper threaded end 30 of the top stick section 5. This plug is formed with a centrally located internally threaded bore 31 for threadedly receiving the top 32 of the umbrella and permitting of the tip being detached from the 15 plug 28 and permanently connecting the cover 33 of the umbrella. The extreme lower edge of the cover 33 is connected to the plug 34 of the lowermost rib section 24.

Pivotally connected in certain of the other 20 of said slots 22 of the collar is a spring 25 pressed trigger 35 adapted when the umbrella is in an unfolded position to engage with the intermediate slot 11 of the top stick section 6 of the umbrella and prevent any 30 accidental movement of the runner with respect to the stick 5 and thereby holding the umbrella in an unfolded position as clearly shown.

From the foregoing description taken in 35 connection with the accompanying drawing, the advantages of construction and of the method of operation will be readily apparent to those skilled in the art to which the invention relates, and while I have described the principles of operation of the device together with the device which I now consider 40

to be the best embodiment thereof, I desire to have it understood that the device shown is merely illustrative and that such advantages may be made when desired as are within the scope of the claim appended thereto. 45

I claim:

An umbrella embodying a stick composed of an upper section, a middle section and a lower section, the said lower section of the 50 stick being threadedly connected with the middle section of the stick, the said top section and middle section having an overlapped portion providing a longitudinally extending V-shaped groove, the overlapped 55 portions of the upper and middle sections also providing ribs, the rib of the middle section engaging in the groove of the upper section for preventing any accidental rotary movement of the latter with respect to the 60 former, means for locking the sections in extended position, a split runner mounted for a sliding adjustment upon the upper and middle sections of the stick, the free longitudinal edges of the runner formed by splitting the same being arranged in an overlapped 65 position for providing the runner with a groove, the groove of the said runner engaging with the rib of the top section for guiding the runner thereon, and spring 70 pressed means pivotally connected with the runner and adapted to engage a slot in the top section of the stick for supporting the umbrella in an unfolded position.

In testimony whereof I have affixed my 75 signature in presence of two witnesses.

JOHN H. COBEL.
